(57) **CLAIM**

The ornamental design for a plug and tap assembly, as shown and described.

DESCRIPTION

FIG. 1 is a perspective view of a plug and tap assembly showing my new design;

FIG. 2 is a further perspective view thereof;

FIG. 3 is a further side perspective view thereof; and,

FIG. 4 is a side perspective view thereof from the left of FIG. 2, the side perspective view from the right of FIG. 2 being the mirror image thereof.
